UNITED STATES PATENT OFFICE.

EDWIN COOPER WILLS, OF EAST ORANGE, NEW JERSEY.

AUTOMATIC CUT-OFF AND CUT-IN VALVE.

Application filed February 29, 1924. Serial No. 696,012.

To all whom it may concern:

Be it known that I, EDWIN C. WILLS, a citizen of the United States, and a resident of East Orange, in the county of Essex and State of New Jersey, have invented certain new and useful Improvements in Automatic Cut-Off and Cut-In Valves, of which the following is a specification.

My present invention relates generally to valves, and more particularly to automatic cut-off valves such as used in connection with gas lines for the purpose of automatically cutting off the supply of gas in case of fire and turn on or cut in valves such as used in sprinkler systems. Various devices have already been proposed with this object in view, but have either been lacking in the effectiveness of their operation or have embodied other disadvantages such for instance as difficulty of inspection, curtailing their usefulness at least to some extent.

One of the known types of cut-off valves which has attained some considerable adoption embodies a ball valve member normally held off of its seat by means of a pin extending through the seat, the pin being formed of a fusible metal so that in the presence of sufficient heat its melting permits the ball to drop by gravity onto the seat and shut off the gas supply. It is a well known fact, however, that when fire occurs gas as well as other pipes lose their supports, and frequently are either bent or dropped to inclined positions wherein the ball when it does fall, fails to find a proper seat and thus fails to function as intended.

The primary object of my invention is the provision of an automatic gas cut-off valve which will avoid the known disadvantages of other valves, which will prevent leakage of gas in the normal position of the parts, which provides for ready inspection from time to time, and which will instantly act upon the melting of a fusible element to force the valve member into effective engagement with its seat for the purpose of cutting off the gas supply.

In the accompanying drawing which illustrates my present invention and forms a part of this specification,

Figure 1 is a vertical longitudinal section through a valve constructed in accordance with my invention,

Figure 2 is a detail perspective view of the valve and its stem with the several parts 55 relatively arranged as in practice in connection with the stem,

Figure 3 is a sectional view through a cut in or turn on valve showing the application of my invention, and

Figure 4 is a detail perspective view of certain of the parts included in the valve of Figure 3.

Referring now to Figures 1 and 2, the body of my improved valve is indicated at 65 10, having internally threaded opposite ends 11 and 12 for connection with sections of a gas line and provided with an intermediate internal diaphragm 13, apertured as at 14 and provided with a horizontally disposed 70 and upwardly presented valve seat 15 around its opening for the reception of a vertically shiftable valve member 16 thereon to cut off the flow of gas through the body. Across its opening 14 the diaphragm 13 has a rib 75 17, apertured at the center of the opening to form a loose guide for a pin 18 depending axially from the valve member 16.

The valve member 16 has upper and lower beveled valve faces 19 and 20, the latter 80 adapted to cooperate with the valve seat 15, and the former adapted to cooperate upon upward movement of the valve member 16 with a valve seat 21 formed within a cap 22, which is threaded in connection with 85 an upper bore of the body 10 above its valve seat 15, and which in turn supports an upright bonnet 23.

Through the cap 22 is an axial opening for the reception of a valve stem 24, the 90 upper end of which projects loosely through a central bearing 25 at the upper end of the bonnet 23 and the lower ball end 26 of which is held within an upper cavity of the valve member 16 by means of a split bushing 27 95 threaded into said valve member.

Threaded into the upper end of the axial opening of the cap 22 is a bushing 28 surrounding the valve stem 24, whose upper surface forms a flat, even, uniform seat for 100

the lower end of a fusible element 29, it being noted that the upper surface of the cap 22 slopes abruptly away from its central portion immediately around the bushing 28, 5 so that the material of which the fusible element 29 is formed may, when this element melts under excessive heat, readily flow away from the valve stem so as to avoid all danger of interference with the proper and 10 desired downward movement of the stem during the seating of valve member 16 upon its lower main seat 15.

It is preferable that the fusible element 29 be formed as particularly shown in Figure 2, with a pair of spaced flat rings 30 connected by a series of circumferentially spaced arms 31, so as to give this fusible element a large seating capacity at both ends thereof and still admit of ready circulation therethrough so as to insure its fusing at the desired temperature.

Above the fusible element 29, whose cylindrical body surrounds the valve stem 24, is disposed a nut 32 upon which is disposed 25 a washer 33, the last mentioned washer forming an abutment for the lower end of a valve actuating spring 34 coiled around the upper portion of the valve stem within the bonnet 23, and whose upper end engages the 30 bonnet around the upper valve stem bearing 25.

In order to cooperate with the nut 32 the valve stem 24 is threaded as at 35, intermediate its ends, and the nut engaging 35 these threads thus provides effective means for shifting the valve stem 24 upwardly in the first instance so as to draw the valve member 16 vertically into engagement with the upper or supplemental seat 19. To do 40 this it is simply necessary to rotate the nut 32, the latter having bearing upon the cap 22, through the fusible element 29 and bushing 28, and it is obvious that when upon installation of the valve as a whole, the valve member is thus shifted vertically into engagement 45 with its supplemental seat 21, all danger of leakage of gas upwardly around the valve stem 24 is avoided.

In operation under excessive heat, the fusible element 29 melts, its material flowing outwardly and downwardly upon the cap 22, so that the valve stem is then forced downwardly by the spring 34 and the valve member 16 connected to and shiftable with the valve stem is thus moved in a straight and guided line on to the main valve seat 15 so as to effectively cut off the flow of gas through the valve body 10.

It is to be noted moreover, that the above action takes place irrespective of the particular position of the valve as a whole, inasmuch as the valve member is effectively guided in its movement and will find its way directly to an even uniform and effective contact with the main valve seat.

It is also to be noted that due to the location of the fusible element and the valve stem actuating parts, including the nut 32 and valve actuating spring 34 immediately above the cap 22 and the cutting away of 70 the lower side portions of the bonnet 23 as indicated at 36 above the cap, provision is made for the ready, efficient inspection of the working parts of the valve whose condition it is important to check from time to 75 time.

Referring now to Figs. 3 and 4 it is plain that my invention may be applied with equal facility to a cut-in or turn-on valve of which the casing 10^a is shown of a construction identical with that of the valve casing 10 of Figs. 1 and 2. Valve member 16^a is also shown of the same construction as the valve member 16 although in the present instance this valve in its normal position seats on the main seat 15^a below the supplemental seat 21^a, the valve in use being arranged so that the fluid, for instance, water, flows in the direction of the arrow. In this construction moreover, the valve actuating spring 34^a is coiled around the valve stem 24^a and compressed between the upper end of the bushing 28^a and a washer 33^a below the nut 32^a. This nut engages a threaded portion 35^a of the stem 24^a adjacent to the upper end of the stem, the nut in this instance bearing upwardly against the lower ring of the fusible element 29^a which in turn seats and bears upwardly against the lower flat surface presented by the upper bearing 25^a of the bonnet 23^a.

In addition to its lower side cut-out portions 36^a the bonnet 23^a has upper side cut-out portions 37^a, it being thus obvious that the adjusting nut fusible element and the adjacent parts may be inspected from time to time as readily as this can be accomplished in connection with the form of construction shown in Figs. 1 and 2, for the purpose hereinbefore outlined. 110

It is also to be noted that my invention proposes means for holding the parts in their actuated position after collapse of the fusible element and the proper and intended action of the springs. In one instance the means just described will operate to secure the main valve in closed position cutting off the supply of gas, against accidental displacement from its main seat within the valve body and in the other case will operate to lock the valve against its supplemental seat and in open position permitting the flow of fluid through the valve body. For this purpose I propose that the bonnet in each instance shall be provided around its upper valve stem bearing with an external housing or cap 38, open at one side and through which the valve stem passes, said cap or housing being adapted to receive a spring lock washer 39 having sufficient tension to spring 115 120 125 130

into an annular groove 40 of the valve stem. In the cut-off valve of Figures 1 and 2 the annular groove 40 of the valve stem is normally positioned above the cap 38 so as to receive the lock washer 39 when the valve 16 descends in the proper contemplated action of the parts upon the main valve seat 15 and in the case of the cut-in valve of Figures 3 and 4, the groove 40 of the valve stem 10 will be positioned below the cap or housing 38 in the normal position of the parts so as to receive the lock washer 39 when in the contemplated action of the parts the valve 16^a moves upwardly against its supplemental 15 seat 21^a.

It is apparent from the foregoing that my improved construction lends itself to just as ready use for one purpose as it does for the other, that is, it is adapted simply by 20 virtue of certain slight rearrangement of some of the parts to function with equal facility as a cut-in valve as it does when used as a cut-out valve. In its use as a cut-out valve it is especially adapted as a gas 25 control valve and in its use as a cut-in or turn-on valve it is especially applicable to sprinkler connections used in sprinkler systems for the prevention of fires.

It is also apparent that with either form of 30 arrangement, my improved valve construction avoids the disadvantages of known valves of the automatic type now in use, and presents a highly efficient device as well as a simple economical structure.

35 I claim:

1. An automatic cut-off valve including a body having a main valve seat, a cap threaded in connection with the valve body having a valve seat spaced from and opposed to the main valve seat, a valve member disposed between said seats and guided in its movement thereto having valve surfaces for engagement with the seats, said cap having a central bore, a valve stem extending 40 through said bore and vertically above the cap, a bushing around the stem within the cap presenting an upper flat face above the cap, a fusible element seated on the bushing, a nut threaded on the valve stem above the 45 said fusible element whereby the valve stem is normally held so as to seat the valve member against the cap seat, a bonnet rising from the cap around the valve stem and having a bearing for said stem, said bonnet having lower side cut-out portions exposing the fusible element and said nut for inspection, and a valve actuating spring around the stem compressed between the 50 said nut and the upper end of the bonnet and also to be seen through the cut-out portions of the bonnet.

2. An automatic cut-off valve including a body having a main valve seat, a cap threaded in connection with the valve body 55 having a valve seat spaced from and op-

posed to the main valve seat, a valve member disposed between said seats and guided in its movement thereto having valve surfaces for engagement with the seats, said cap having a central bore, a valve stem extending 70 through said bore and vertically above the cap, a bushing around the stem within the cap presenting an upper flat face above the cap, a fusible element seated on the bushing, a nut threaded on the valve stem above the 75 said fusible element whereby the valve stem is normally held so as to seat the valve member against the cap seat, a bonnet rising from the cap around the valve stem and having a bearing for said stem, 80 said bonnet having lower side cut-out portions exposing the fusible element and said nut for inspection, a valve actuating spring around the stem compressed between the said nut and the upper end of the bonnet and 85 also to be seen through the cut-out portions of the bonnet, said valve stem having a lower angularly shiftable connection with the upper portion of the valve member, as described. 90

3. A cut-off valve including a valve body having vertically spaced valve seats, a valve member guided therein and shiftable between the said seats, a valve stem extending through the portion of the body adjacent to 95 one of the seats and having connection with the adjacent side of the valve member, a fusible element around the valve stem exteriorly of the body, a valve stem guide in connection with the body forming a flat seat 100 for one end of the fusible member, a nut against the other end of the fusible member having a threaded connection with the valve stem, a bonnet extending from the valve body, having a guide for the outer portion 105 of the valve stem and having cut-away portions at its opposite sides adjacent to the valve body, and a spring around the valve stem compressed between the said nut and a portion of the said bonnet, and exposed to 110 view with the said nut and the fusible element through the cut-away portions of the bonnet.

4. An automatic valve including a valve body having spaced opposing valve seats, 115 a valve member shiftable between and on to said seats, a valve stem extending from one side of the valve member exteriorly of the body, a spring in connection with the said stem for shifting the valve on to one of said seats, a member threaded on the valve stem and rotatable to force the valve against the other of said seats, and a fusible element normally engaged by said threaded member and forming an abutment therefor, said 120 stem having an extension beyond said threaded portion, and a protecting bonnet having a guide at its outer portion for the said stem extension, the bonnet and stem extension having automatically engageable 125 130

means for locking the valve against the first mentioned seat after actuation in order to prevent accidental displacement thereof.

5. An automatic valve including a valve member having spaced valve faces, spaced valve seats between which said member is shiftable, means for normally holding said member in engagement with one of said seats including a fusible element, collapse of

10 which frees the valve member, a spring for

forcing the valve when free onto the other seat, and means to lock the valve after actuation in connection with its last mentioned seat, including an annularly grooved stem projecting from the valve and a spring en- 15 gaging the stem and adapted to project into the groove of the stem when the latter is moved opposite to the washer.

EDWIN COOPER WILLS.
